HAIR CURLING DEVICE

Filed Dec. 30, 1938

UNITED STATES PATENT OFFICE

2,163,524

HAIR CURLING DEVICE

Leonard George Arpin, Jackson Heights, N. Y.

Application December 30, 1938, Serial No. 248,414

10 Claims. (Cl. 132—35)

My invention relates to hair curlers and more particularly to a curling device embodying means for both forming curls, and, in combination with a hair pin, means for maintaining the hair in a curled position. The invention also contemplates a novel method of accomplishing the above.

Until recent times hair curling by individuals has been effected either by a heated iron, or by a number of curlers which curled the hair sections and clamped the curl against unwinding. Each curl required a separate curler and the obvious disadvantages inherent in such a procedure has stimulated new inventions to effect the desired result in a less cumbersome fashion. These inventions generally comprise a tubular rod having a clamping member hinged thereon and a hair pin retained in the tubular rod. When the hair section has been clamped and wound around the tubular rod, the clamp is released and the resulting curl is pushed laterally until it is disposed between the shanks of the hair pin, which shanks have been maintained separated. At this point, the shanks of the hair pin are caused to approach one another, thus clamping and maintaining the curl against unwinding.

This procedure has entailed some disadvantages of its own among which are the inability to form a good curl on the tubular rod, and the further distortion of the curl when it is manually pushed so as to approach the hair pin. In addition, the release of the clamping member of the tubular rod to enable the curl to be pushed, necessarily loosens the curl immediately prior to its deposit within the confines of the hair pin.

Bearing the foregoing in mind it is an object of the present invention to provide a device for forming a more perfect curl while eliminating the necessity for a clamping member.

Another object of my invention is to combine a comb with such a device, so that the combing of the hair is automatically accomplished while the hair strands are being prepared for curling.

Another object of my invention is to provide for curling hair wherein the curl need not be pushed between the separated shanks of a hair pin but, on the contrary, the hair pin, the shanks thereof being in substantially normal, i. e. clamping relationship, is directed toward the curl while it is wound around the device so that the hair pin, and not the curl, receives the force of effecting the union.

A further object of my invention is to provide in combination with such a device, a hair pin of novel construction which can be applied to a curl while the shanks thereof are maintained in a

substantially normal and clamping relationship. Another object of my invention is to provide novel means for both maintaining the comb in operative position and retracting the comb when the curl has begun to form.

Other objects of my invention will be apparent from the following description, it being understood that the above general statements of the objects of my invention are intended to describe and not to limit it in any manner.

Referring to the drawing:

Fig. 1 is a side elevational view of the device, with the retractable comb teeth in locked projected position, some of said teeth being omitted for the sake of clarity.

Fig. 2 is a similar view with the retractable comb in the inoperative position and locked thereat.

Fig. 3 is an enlarged fragmental sectional view, the retractable comb being in the inoperative position and locked thereat.

Fig. 4 is a section on the line 4—4 of Fig. 3.

Fig. 5 is a perspective view of the locking device.

Fig. 6 is a section on the line 6—6 of Fig. 3.

Fig. 7 is a side elevational view of the hair pin. In the drawings, the device as illustrated comprises the curling section A and the integral handle section B. The handle section B may be in the form of a comb for purposes of convenience but this is unnecessary for the operation of the device.

The curling section A is formed as a hollow member of substantially U-shaped cross-section, the outer end 10 being planar and having a bore 11 at the base thereof. A ledge member 12 inserted at the top thereof extends beyond the end wall 10 for a purpose to be hereinafter set forth.

A post 13, integral with the base 17 of section A, cooperates with the adjacent end of section B to anchor, as by frictional means, a spring wire 14, whose force is directed upwardly at its free end.

The base 17 of section A may have formed on its inner surface a groove 15 which is disposed so as to constitute a continuation of the bore 11 when said opening advances beyond the member 16 formed integral with the end wall 10. The base 17 further has a depression 18 formed thereon, the purpose of which will be hereinafter described.

The retractable comb 19 comprises comb teeth formed integral with its base 21, the lug 22 being disposed at one end of the base 21, the other end thereof generally comprising the manipulating member 23. Said manipulating member 23

has a substantially C-shaped slot 24 formed therein, the lower leg of said slot having a sunken level 25. For ease and certainty of manipulation, a saddle 26 having a knurled edge is formed on the outer end of the member 23.

A locking member 27 is effective to maintain the retractable comb 19 within section A, in either the projected or retracted position. The locking member 27 comprises substantially pendant-shaped walls 28 and 29 bridged by the portion 30 and having a slot 31 formed therein. While the slot as shown herein is T-shaped, said shape is immaterial to the operation of the device, the shape being decorative while the slot itself is functional. In addition, the wall 29 is formed with a lip 31a.

The retractable comb 19 is assembled within section A by inserting one wall of the locking member 27 into the slot 24 of the manipulating member 23 and giving the locking member 27 a half-turn whereby the bridge 30 thereof will be disposed across the vertical leg of the slot 24. The widest portion of the walls 28 or 29 should be of slightly greater width than the vertical leg of the slot 24 so that the assembly is effected by forcing the locking member 27 through said slot 24, which action will discourage an inadvertent dis-assembly of the device. The lug 22 is then placed under the ledge 12 as in Fig. 1, and the locking member is caused to straddle the section A at a point which is adapted to retain said locking member. This is accomplished by ridges 32 and 33, and a projection 34, all of which are integral with the side wall 35 thereof. The projection 34 is received within the slot 31 and the locking member 27 is further insured against undesired movement by the bounding ridges 32 and 33. These ridges may also be formed on the opposite wall and they perform the further function of guiding the locking member 27 when effecting the assembly of the comb 19 with section A.

When the retractable comb 19 has been thus assembled as shown in Fig. 1, the bridge 30 will be disposed in the sunken level 25 of the slot 24 and the locking member 27 being anchored as aforesaid to section A, the retractable comb 19 will be locked in the position shown in Fig. 1. The lug 22 will also be frictionally restrained by the ledge 12 while the spring wire 14, bearing against the back of the comb 19 urges the comb to its operative position.

In order to retract the comb, the manipulating member 23 may be directed toward section B whereby the bridge 30 will leave the level 25 and will be disposed in the vertical leg of the slot 24. The comb may then be depressed by applying the force of the finger F to the saddle 26 whereby the comb will be lowered, against the action of the spring wire 14. The comb 19 may then be locked in this retracted position by sliding it forward with the finger, the bridge 30 then entering the upper horizontal leg of the slot 24 thereby locking the comb as shown in Fig. 2.

A hair pin 36, made of metal or any other suitable material and known in the art as a "bobby pin", has a substantially straight shank 37 thereof disposed in the bore 11, while the hump 38 of the shank 39 nests in the depression 18 of the base 11.

My invention is practiced in the following manner:

The device in the position shown in Fig. 1 is applied to a tress of hair, the retractable comb 19 combing the hair tress. A few strokes are suf-

ficient to satisfactorily comb said tress and, the comb 19 being drawn to the outer end of the tress, the device is turned so as to cause the tress to curl around section A and to be located wholly within the confines of the two comb teeth defining the width of the curl. Thus a well formed curl is prepared for the subsequent operation which prevents its unwinding. The foregoing procedure for a different purpose has been described in Patent No. 2,137,828 granted to me as co-inventor on November 22, 1938.

When the curl has been sufficiently formed thus and the device has approached the scalp, the comb 19 is retracted and housed within the hollow of section A by applying the necessary movements to the manipulating member. The comb 19 is thereby locked in the inoperative position while the slight slack in the curl can be drawn up by slightly drawing on the device.

At this point it is possible to turn the device relative to the curl, that is, within the curl and the hair pin 36 which is fixed relative to the device can be thus caused to turn and thereby to lie adjacent any portion of the curl which the operator considers will be most desirable. This having been accomplished and the curl being wound around the section A while the comb 19 is housed therein, the hair pin 36 is pushed further into the bore 11, the shank 37 sliding along the groove 15 and the shank 39 which is formed with an uplifted end, embracing and clamping the curl against the base 11 of the device. Thus the curl is clamped against unwinding before it is removed from the device so that its subsequent removal is not attended with an unnecessary distortion of its shape and the union is effected without manipulating the curl which has been formed as desired. The uplifted end of the shank 39 insures the necessary clamping of the curl without initially disturbing the effect theretofore achieved.

The device is then removed whereby another hair pin may be inserted and another curl formed. The removal is accomplished by grasping the curl and hair pin with one hand and withdrawing the device with the other. The curl therefore remains and is maintained against unwinding by the air pin which may be so disposed as not to be visible.

The locking member 27 is formed with the lip 31a to facilitate the disengagement of the retractable comb 19 with section A so to permit of the cleaning or other treatment of the comb 19. This locking member 27 may be made of metal or any other suitable material, while the entire device is fashioned preferably from suitable moldable material such as "Bakelite" or other well known plastic.

I have shown a preferred embodiment of my invention but it is obvious that numerous changes and omissions may be made without departing from its spirit. For example while I have shown my invention as operating with one hair pin, it may be desirable to provide the end wall 10 with two or even more bores like bore 11 so that a plurality of hair pins may be simultaneously applied to the curl. One of these hair pins may be decorative, as embedded with jewels or formed of a brightly hued plastic or metal, and may be applied so as to be visible. It will be obvious that should a hair pin of decorative nature be employed, my device enables it to be applied where it will be visible as desired.

I claim:

1. A hair curling device comprising a body por- 75

- tion having an elongated slot, a comb member 5
slidable in said slot a manipulating member having a C-shaped slot formed therein integral with said comb member and a substantially U-shaped locking member straddling said body portion and cooperating with said C-shaped slot to lock said comb member in the operative or inoperative positions and to prevent displacement of said comb member from said elongated slot.
- 10 2. A hair curling device comprising a first member around which hair can be spirally wound, a second member connected to said first member for engaging a tress of hair, and a hair pin disposed substantially laterally of said members, the shanks thereof being maintained by said holder in substantially normal and clamping relationship.
- 15 3. A hair curling device comprising a body portion for engaging a tress of hair and for winding said tress into a curl and a hair pin maintained on said body portion and substantially laterally thereof, the shanks of said hair pin being maintained in a substantially normal and clamping relationship, one shank of said hair pin having 20 its end offset in respect to the end of the other shank whereby said hair pin can be actuated to clamp said curl without spreading said shanks from said substantially normal and clamping relationship.
- 25 4. A pair curling device comprising a first member around which hair can be spirally wound, a second member connected to said first member for engaging a tress of hair, said first member having an opening at one end thereof and having 30 a depression at the base thereof said opening being adapted to receive one shank of a hair pin and said depression being adapted to engage a hump on the other shank of said hair pin, the disposition of said opening and said depression being such that said hair pin is supported with the shanks thereof in substantially normal and clamping relationship.
- 35 5. A hair curling device comprising a mandrel about which hair is adapted to be wound, said mandrel having an opening at one end thereof for receiving one shank of a hair pin and having means at said end for engaging a hump near the end of the other shank of said hair pin, said opening and engaging means being operative to 40
- support said hair pin so that the shanks thereof are maintained in a substantially normal clamping relationship.
- 5 6. In combination, a hair pin having a hump near the end of one shank thereof and a holder having an engaging element at one end thereof said engaging element being complementary to said hump, said holder comprising a body portion having an elongated slot and comb member 10 slidable in said slot, means for acting against said comb member to urge it outwardly to the operative position, said hair pin being maintained by said body portion substantially laterally of said comb member by engaging said hump with said complementary engaging element of the holder, 15 and means to retract said comb member to the inoperative position.
- 20 7. In combination, a hair pin having a hump near the end of one shank thereof and a holder having an engaging element at one end thereof, 20 said engaging element being complementary to said hump, a hair engaging member connected to said holder, said hair pin being maintained by said body portion substantially laterally of said hair engaging member by engaging said hump 25 with said complementary engaging element of the holder, and means for urging said hair engaging member to the inoperative position.
- 25 8. A hair curling device according to claim 7 wherein said locking member is provided with a 30 bridge piece and said C-shaped slot is provided with a sunken level on its lower leg whereby the location of said bridge piece in said sunken level locks said comb member in the operative position.
- 30 9. A hair curling device comprising a body portion having an elongated slot, a comb member retractile in said slot, and a detachable locking member for locking said comb member in the operative or inoperative positions and for preventing displacement of said comb member from 35 said elongated slot.
- 35 10. A hair curling device according to claim 9, wherein said locking member comprises a U-shaped element of resilient material straddling a portion of said slot of said body portion whereby to prevent displacement of said comb member and engaging said comb member whereby to lock it in the operative or inoperative positions.

- tion having an elongated slot, a comb member 5
slidable in said slot a manipulating member having a C-shaped slot formed therein integral with said comb member and a substantially U-shaped locking member straddling said body portion and cooperating with said C-shaped slot to lock said comb member in the operative or inoperative positions and to prevent displacement of said comb member from said elongated slot.
- 10 2. A hair curling device comprising a first member around which hair can be spirally wound, a second member connected to said first member for engaging a tress of hair, and a hair pin disposed substantially laterally of said members, the shanks thereof being maintained by said holder in substantially normal and clamping relationship.
- 15 3. A hair curling device comprising a body portion for engaging a tress of hair and for winding said tress into a curl and a hair pin maintained on said body portion and substantially laterally thereof, the shanks of said hair pin being maintained in a substantially normal and clamping relationship, one shank of said hair pin having 20 its end offset in respect to the end of the other shank whereby said hair pin can be actuated to clamp said curl without spreading said shanks from said substantially normal and clamping relationship.
- 25 4. A pair curling device comprising a first member around which hair can be spirally wound, a second member connected to said first member for engaging a tress of hair, said first member having an opening at one end thereof and having 30 a depression at the base thereof said opening being adapted to receive one shank of a hair pin and said depression being adapted to engage a hump on the other shank of said hair pin, the disposition of said opening and said depression being such that said hair pin is supported with the shanks thereof in substantially normal and clamping relationship.
- 35 5. A hair curling device comprising a mandrel about which hair is adapted to be wound, said mandrel having an opening at one end thereof for receiving one shank of a hair pin and having means at said end for engaging a hump near the end of the other shank of said hair pin, said opening and engaging means being operative to 40
- support said hair pin so that the shanks thereof are maintained in a substantially normal clamping relationship.
- 5 6. In combination, a hair pin having a hump near the end of one shank thereof and a holder having an engaging element at one end thereof said engaging element being complementary to said hump, said holder comprising a body portion having an elongated slot and comb member 10 slidable in said slot, means for acting against said comb member to urge it outwardly to the operative position, said hair pin being maintained by said body portion substantially laterally of said comb member by engaging said hump with said complementary engaging element of the holder, 15 and means to retract said comb member to the inoperative position.
- 20 7. In combination, a hair pin having a hump near the end of one shank thereof and a holder having an engaging element at one end thereof, 20 said engaging element being complementary to said hump, a hair engaging member connected to said holder, said hair pin being maintained by said body portion substantially laterally of said hair engaging member by engaging said hump 25 with said complementary engaging element of the holder, and means for urging said hair engaging member to the inoperative position.
- 25 8. A hair curling device according to claim 7 wherein said locking member is provided with a 30 bridge piece and said C-shaped slot is provided with a sunken level on its lower leg whereby the location of said bridge piece in said sunken level locks said comb member in the operative position.
- 30 9. A hair curling device comprising a body portion having an elongated slot, a comb member retractile in said slot, and a detachable locking member for locking said comb member in the operative or inoperative positions and for preventing displacement of said comb member from 35 said elongated slot.
- 35 10. A hair curling device according to claim 9, wherein said locking member comprises a U-shaped element of resilient material straddling a portion of said slot of said body portion whereby to prevent displacement of said comb member and engaging said comb member whereby to lock it in the operative or inoperative positions.
- 40 LEONARD GEORGE ARPIN.
